Del., a Corporation of Delaware

Application December 18, 1928
Serial No. 326,878

9 Claims. (Cl. 209—469)

The invention relates to a new and useful process and mechanism for separating intermixed divided materials wherein the parts or particles vary relatively greatly in size and vary relatively little in specific gravities.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a side elevation of a mechanism embodying the invention;

Fig. 2 is a vertical transverse section on line 2—2 of Fig. 1;

Fig. 3 is a detail section of the shutter valve, taken on line 3—3 of Fig. 2;

Fig. 4 is a fragmentary detail section taken on line 4—4 of Fig. 1, showing a bearing for the shutter valve shaft journalled in the side wall of the main air chamber;

Fig. 5 is a top plan, partly diagrammatic, of a double table embodying the invention;

Figs. 6 and 7 are diagrammatic sections similar to Fig. 2, showing different settings of the shutter valve;

Fig. 8 is a top plan similar to Fig. 5, with parts broken away, showing a modification of the table provided with sub-area zoning; and

Fig. 9 is a fragmentary longitudinal vertical section of the deck shown in Fig. 8.

The invention pertains broadly to the separation of intermixed, divided materials, the term "divided" being used to designate broken, fragmentary, granular, pulverulent or other materials comprising separated parts or pieces of different kinds of material. The invention in its novel features is more particularly directed, however, to effecting automatic separation, to practically the ultimate degree of possible efficiency, of such mixtures of materials wherein the various pieces of the different kinds of materials vary relatively very greatly in size, while varying relatively little in their specific gravities.

With this purpose in view, the invention is

further directed to effecting, concurrently with the separating process, an approximate size classification both, of the impurities and of the coal, whereby there is attained unusual and practically perfect efficiency in cleaning and separating such widely varying unsized materials. In combination with the concurrent separating and sizing operations effected by the process, the invention provides for the subjecting of the intermixed materials to the combined action of various forces, and to a very nice regulation and control in the application of said forces, whereby all the particles comprising the mass of materials to be separated are subjected to exactly the proper combination of forces in exactly the proper relative amounts, whereby the most complete and rapid separation of the materials is effected and maintained.

One kind of intermixed divided materials which the invention is especially capacitated to successfully separate, is a mixture of coal, "bony" and rock, with the other impurities usually present in the coal, as it comes from the mine, that is, "run of the mine" coal, except that the large lumps, say from seven inches up are crushed, although this crushing is not necessary even up to pieces ten inches in size. Usually, however, it is simpler to remove a few large chunks of coal and rock than to run them over separating tables. The rock and other impurities are separated from the "run of mine" coal by the present invention entirely automatically, on a single cleaning table, and without previous sizing of the materials, except as to said crushing or removing the very largest lumps, the practically perfect separation being effected down through the finest dust of the intermixed materials.

The conditions of the inventive problem solved by the invention are of the greatest practical difficulty due to the wide range of variations in the sizes of the pieces or particles of the intermixed materials, and concurrently therewith the relatively small differences in the specific gravities of the materials, and due further, frequently, to a very high percentage of impurities in the finer part of the mixture. Separating work of this kind, with these factors present, requires practically an entirely different process and mechanism or apparatus from the separation of materials which are very finely pulverized and which vary very widely in their specific gravities on the one hand, or which, on the other hand, are very carefully and extensively sized prior to the separating process. This is especially true in the separation of coal, particularly bi-

tuminous coal, different lots or runs of which may vary greatly in their characteristics, especially as to the ratio of coarse particles to "fines", the amount of impurities in the "fines" or in the 5 larger sizes, the friability of the particles, and in the frictional qualities of the coal and impurities.

The terms "lighter" and "heavier" as used hereinafter will be understood as applying to the specific gravities of the various intermixed, 10 divided materials and not to the difference in mass of particular pieces of various sizes.

According to previous commercial practice in separating or cleaning intermixed materials varying relatively greatly in sizes of the pieces or 15 the particles, while varying very little in the specific gravities of the materials, and especially in the cleaning of coal, it has been necessary to very closely size the coal by preliminary screening before attempting the automatic separation 20 of the intermixed coal, bony, rock and other impurities. This previous commercial practice has necessitated the employment of a large number of screening or sizing devices, and likewise a corresponding number of small tables for separately 25 cleaning the thus sized or classified coal, one table being necessary for each of the sized classifications of the coal created by the screening devices. It has been quite usual to employ six or eight screens and the same number of 30 small cleaning tables to clean run-of-mine coal, of sizes, say from three inches down, while efficient cleaning of the larger sizes has been impossible of accomplishment by such tables.

The present invention as preferably practiced 35 comprises feeding the unsized run-of-the-mine coal onto an air-pervious table or deck at a regulable rate, so as to maintain substantially uniformly upon the table a bed of the materials of appreciable thickness, usually several inches in thickness. This bed is progressed forwardly and simultaneously undergoes gradual separation 40 into horizontally-disposed strata, the superior one of clean coal, and the inferior one of the impurities, by reason of the longitudinal reciprocation of the bed and forcing upwardly through the bed lifting air currents. The coal, 45 as the lighter material, is floated in a superior stratum and the impurities, as the heavier material, comes to rest upon the table, and are thence impelled forwardly by friction and inertia to discharge along a predetermined path.

For most rapidly and efficiently effecting the horizontal stratification of the bed of materials 50 so as to properly accommodate the various sized particles, the lifting air currents forced through the bed are preferably of a wave-like or pulsating nature, the intensity of the air force being continuously modified between upper and lower pressure limits, whereby a series of recurrent waves 55 of air is passed upwardly through the bed. By virtue of this continuous and recurrent modification of the air forces, each particle in the bed of materials is, at some time during the modulations of an air wave, subjected to exactly the proper stratifying conditions. On the other hand, the maximum intensity or upper limit of the air waves is never so great as to disturb the stratification already established in the bed or to 60 remix the separating materials. Usually the rapidity of stratification is greatly promoted by the use of air waves as distinguished from a steady blast.

In combination with the wave-like modulations of the lifting air force, the air forces in 65 the different parts of the bed may preferably,

although not necessarily, be further regulated by providing zones of varying air-perviousness at different parts of the air-pervious deck, these zones being preferably arranged along the deck in gradated relation both forwardly and laterally of the deck. Hence there is provided a constant air-controlling factor for each zone, superimposed upon the continuously changing air waves forced through the deck.

In addition to the regulations of the lifting air forces hereinbefore mentioned, in certain cases and with certain types of coals or other materials, a further regulation of the air forces may be employed. According to the invention, stratification and separation of the materials in the bed may be greatly expedited and perfected by subjecting different areas of the bed to air waves having different upper and lower pressure limits. That is, certain areas of the bed, and preferably those in which the primary stratification of the coarser impurities takes place, are subjected to recurrent lifting air waves whose pressure intensities vary between a maximum and an intermediate limit. Other areas of the bed, and preferably those wherein the stratification of the finer particles is accomplished and perfected, are subjected to air waves which vary between an intermediate and a maximum pressure limit. The extents of the different areas so treated and the pressure limits may be varied as necessary or desired.

A further refinement of the air control which may be optionally employed in certain cases and with certain kinds of coals consists in further selectively regulating the amount of air supplied to different parts of the bed of materials in various sub-zones or sub-areas within the respective areas or zones of different air-perviousness; this selective regulation in the various sub-zones being susceptible of exceedingly nice gradation 100 through a very wide range.

Hence, the lifting air currents which pass through the bed may be subjected to a combination of different controlling and regulating factors which cooperate to provide exactly the proper stratifying and separating forces at each point in the bed of materials. Furthermore, the regulating features described in combination with other regulating features provided by the invention, can be used to so modify or "tune" the separating conditions in the bed of materials to provide a practically perfect separating action for coals having any given combination of characteristics and for coals presenting exceedingly difficult problems of separation.

It will be understood that the foregoing general description and the following detailed description as well are exemplary and explanatory of the invention but are not restrictive thereof.

Referring now in detail to the embodiment of the invention illustrated by way of example in the accompanying drawings, an air pervious table 10 is shown consisting preferably of two halves or parts, which may be of similar construction but in reverse position. The deck 10 is provided with an upwardly projecting, bed-retaining wall 11 across the rear end thereof, and with upwardly-projecting, bed-retaining walls 12 and 13 extending along either exterior side of the table from the rear wall 11 preferably to the front ends of the table. The discharge edge for the lighter superior stratified material is preferably in the form of a transversely inclined spillage edge 14, extending from the forward outer edge of one side of each table, or each half of the table backwardly

and inwardly for a relatively large proportion of the length of the table. If desired, also, there may be a central, upwardly-projecting, longitudinally-extending partition 15, from the rear wall

5 11 to the innermost point of the spillage or delivery edges 14 for the lighter superior stratified material.

The two halves of the table may both be inclined transversely upwardly and outwardly, and 10 this degree of inclination may be varied. In certain cases it may even be desirable to incline the halves of the table downwardly and outwardly. It will be understood that either half of the table could be used as a single table if desired, in so far 15 as concerns many features of the invention.

The pervious table deck 10 is supported upon a suitable frame structure, consisting of longitudinally and transversely-disposed channel-beams 19 and 20, and this structure, with certain other 20 portions later to be described, are longitudinally reciprocated through a short path to impel the bed of materials lengthwise of the table. With this in view, the frame structure 19, 20 is pivotally mounted upon the upper ends of a plurality 25 of arms 21, the lower ends of the arms in turn being pivotally mounted upon the side members 27 of the stationary structure of the air chamber. The arms are preferably inclined upwardly and backwardly when the table is at the rear end of 30 its stroke, so that the path of reciprocation of the table is upward and forward and downward and backward. The fixed portion of the stationary air chamber 29 is attached to the frame 27, and is clearly shown in Figs. 1 and 2, and need 35 not be described in detail. It is preferably decreased cross-sectionally gradually forwardly of the table to more effectively control the air pressure lengthwise of the table. A suitable air-impermeable flexible connection 30 connects the reciprocable table with the stationary air chamber. 40 The embodied means for supplying the air current comprises a rotary fan 35, which is equipped with some suitable form of air current regulating means such as a slide 36 applied to the intake 45 opening of the fan. The fan connects by a conduit 37 with the air chamber 29. Thereby the intensity of the air current supplied to the entire table can be primarily controlled.

The table is preferably variably upwardly and 50 forwardly inclinable, the front end in most cases being slightly higher than the rear end, although this slope may be reversed if required. In the embodied form, the table is provided at either side near the rear thereof with pivot bearings 40, and 55 a plurality of screw posts 41 are arranged as supports along and beneath the stationary side frames 27 of the air chamber. A suitable power driven feeding mechanism 44 is provided for feeding a regulable amount of material to the rear 60 end of the table.

The embodied means for reciprocating the table comprises a link 45, connected at its forward end to the rear reach of the frame 19, 20, and connected at its rear end to an eccentric 46 fixed on a shaft 47, which shaft is journaled in suitable bearings and mounted upon a suitable support 48. The shaft 47 is driven in any suitable manner, as 65 by a belt and pulley 49.

70 Cooperating with the reciprocating means is a suitable spring buffer mechanism, which preferably is always under tension and designed so that the degree of tension does not vary greatly during the short path of reciprocation of the table. As embodied a plurality of rods 50 extend 75 forwardly from the front end of the table and

are reciprocable in apertures in a fixed support 51. On the opposite side of the support 50 helical springs 52 encircle the rods, and are provided with tension-adjusting nuts 53.

In the embodied form of table, separating partitions are provided which act both during the separating process, and later to impel the settled heavier material by friction and inertia to the desired place of delivery. As embodied, these separating partitions 55 are inclined forwardly and outwardly, for the purpose of directing the heavier material which has settled upon the deck by the shortest and quickest route to the side edge of the bed to be discharged therefrom at a median point in the length of the bed. By directing the heavier material to the edge of the bed as soon as it settles behind a separating partition, fractional and substantially immediate discharge of all the settled heavier material is rendered possible.

The superior layer of stratified lighter material is given an unimpeded flow directly forwardly along the table, and is discharged freely across the whole length of the forward end of the table, and is provided with an ample spillage 100 edge 14, which is much greater in length than the width of the table. Furthermore, the heavier material which has settled upon the deck, is impelled by friction and inertia quickly and shortly to the side of the table and is discharged practically immediately upon reaching said side edge. This avoids the inconvenience and disadvantage of accumulation of a large, wide and thick bed of this heavy impure material, with the consequent unnecessary work of reciprocating it for a relatively long period of time, and with the attendant disadvantage of a crowded or congested movement of the lighter materials on the table and the remixing to some degree of the heavier and lighter materials.

As stated, the heavier material is discharged from the bed practically immediately upon its reaching the side edge thereof, apertures being provided along the side walls 12 and 13 for permitting egress of the separated impurities. The discharge of the heavier materials through these apertures may be very closely regulated by the provision of discharge devices 60, which may be the same or similar to those shown in the co-pending application Ser. No. 200,080, of Kenneth Davis, and need not be described in detail, as the specific structure thereof constitutes no part of the present invention. The headers for supplying air currents to the discharge devices are indicated by 61 and 62, and the flexible connections therefrom by 63, the headers receiving the air currents by means of connections 65 and 66 from the main air chamber. The amount of air directed into the refuse discharge boxes 60 may be varied by the belts 66 encircling the flexible 120 connections 63.

As hereinbefore set forth, one of the principal features of the invention comprises the various selectively operable means for varying and controlling the intensities and amounts of air passed through the bed at different times and at different areas thereof. Among these air-regulating means, the invention provides a gradated zoning of the perviousness of the air-permeous surface 145 of the deck, different areal zones thereof being preferably covered with perforated metal sheets having different percentages of perviousness. It will be understood, however, that the zoning of the deck may be effected by other means, that 150

described being exemplary but not restrictive of the invention.

So far as concerns most features of the invention, the zoning of the air currents, that is, the variation in air-perviousness of the deck, may be variously arranged. As shown, the air current area or zone of greatest perviousness is at the rear of the table, the intensity decreasing forwardly as indicated by the letters A to D. The arrangement shown is usually preferable and the one most generally employed. However, there may be situations where the zoning may be the reverse of that shown, that is, with the air perviousness increasing forwardly along the table. With the zoning shown, it will be understood that the forwardly-moving bed of materials on the table progresses through gradated zones of a continuously decreasing air force while the transversely-moving heavier materials, generally speaking, also progress laterally outwardly into areas of decreasing air-perviousness.

Another feature in the regulation of the air forces comprises continuously modifying the intensity of the entire current of air supplied to the air chamber to produce a series of recurrent waves of lifting air force whose intensities vary between upper and lower limits. This recurrent modulation of the air intensity may be employed either with the deck zoning hereinbefore-described, or, in other cases, may be employed independently of the areal zoning, the latter being dispensed with and the wave-like modifying of the air currents being performed on an air current passing through a deck of uniform perviousness, the question of whether or not the two features will be combined or the pulsating current be used alone being largely determined by the characteristics of the material to be separated.

The present preferred means for effecting the wave-like or pulsating air current comprises a rotary shutter or butterfly valve 70, mounted within the main air chamber 29 on a transversely-disposed shaft 71, which is journaled in the side walls of the chamber 29, the walls being preferably provided with hubs or bosses 72 for receiving and supporting the ends of the shaft. The rotary shutter 70 may be operated in any manner desired, as by means of a driving sprocket 75 keyed to shaft 71 and driven in any suitable manner as by chain 76 from a sprocket 77 on shaft 47. The shutter may be driven or controlled by any known or suitable variable-speed device if desired, to produce the wave-like air action through the bed; or the shutter 70 may be stationary, in horizontal position, thereby permitting a continuous or non-pulsating lifting air current action through the bed. It will usually be found most efficient to time the rotation of the controlling shutter with the reciprocating movement of the table, by effecting a half-rotation of the shutter for each complete reciprocating movement of the table. With many kinds of materials to be separated, the wave-like air blast will be timed so that the shutter will begin to open and go to full open or horizontal position on the forward stroke of the table, and will then go to the closed position, at the half-revolution on the backward or return stroke of the table. This will prevent any backward sucking on the return stroke of the table, and will secure the full separating effect of the pulsating air blast.

Means are provided by the invention for subjecting different areas of the table surface to air waves having different intensity limits, whereby one area of the table may be receiving waves of

air force which vary in intensity between a major and an intermediate pressure limit, while another area receives waves varying between intermediate and minor pressure limits. In the arrangement shown in Figs. 1 and 2, the area of the bed to the rear of the shutter valve 70 is subjected to air pressure waves whose limits of intensity vary between a maximum of pressure equivalent to the entire air force delivered by the fan and localized by the damming effect of the shutter which closes the entire cross-sectional area of the air-chamber, except for some possible slight leakage around the edges; and whose lower limit of pressure intensity occurs when the shutter is in the horizontal or full-open position, at which time the rear area of the bed is subjected to the normal portion of air pressure which it would receive if the air-chamber were unobstructed by the shutter valve. The forward area of the bed, on the other hand, receives air waves varying in pressure between the normal or intermediate pressure produced when the valve is in its horizontal full-open position and the minimum pressure created when the valve is in the closed or vertical position. In the latter position, the forward area of the bed receives a minimum of zero, or atmospheric, pressure. It will further be noted that the pressure waves in the rear and forward areas of the bed are diametrically out of phase, the maximum intensity in the rear area occurring when the air is entirely shut off in the forward area, while the normal or full-open shutter produces the minimum limit in the rear area and the maximum limit in the forward area. A screen 78 of canvas or the like may be hung above the top of the shutter to provide an air seal between the shutter and the bottom of the decks.

Means are provided for varying the pressure limits to which the different areas of the bed are subjected. For instance, in some cases it may be desirable to subject the forward area of the bed to pressure waves whose minimum intensity is above atmospheric pressure and in such cases it may also be desirable to subject the rear area of the bed to a blast whose upper limit of intensity is less than the producible maximum, whereby the pressures throughout the bed as a whole are more uniform. As embodied, the shutter valve 70 is preferably formed so as to be variable in extent, whereby the effective diameter of rotation of the valve may be varied within desired limits. In Figs. 2 and 3 the shutter 70 is shown composed of two fixed blades 80 and 81 extending from a winged sleeve 82 mounted to rotate on shaft 71. The blades 80 and 81 are adapted to support extensible wing members 83 and 84 at their respective outer ends, said wings 83 and 84 being attached to the blades 80 and 81 respectively by bolts 85 engaging with slots 86 in the wings, whereby the effective diameter of the shutter may be lengthened or shortened as desired.

As will be clear from Figs. 6 and 7, the diameter of the shutter may be reduced to occupy only three fourths or other fraction of the cross section of the air chamber. This may be done as shown in Fig. 6, by spacing the wings 83 and 84 equally from the central shaft, or, as shown in Fig. 7 by moving one of the wings to provide the whole area of clearance. In either case, it will be understood that the rotating shutter never entirely closes off the supply of air from the fan 35 to the forward portion of the bed. Therefore, the maximum limit of pressure in the rear

area (that area to the rear of the shutter shaft) is maintained lower by the escape of air around the edge or edges of the shutter when in its vertical position, while the minimum limit of the forward area never falls to zero, but at its minimum is equivalent to the pressure of the air which escapes around the shutter.

In accordance with one feature of the invention, the differential pressure areas created by the position of the shutter valve relative to the bed may be varied so as to vary the area subjected to the pressure waves of higher or lower limits. As embodied, the side walls 29 of the air chamber are provided with a plurality of apertures 90 and shaft bearing hubs 72 for the reception of the shaft 71, whereby the shaft and shutter may be moved to any one of the various positions shown to thereby vary the relative extents of the differential pressure areas of the bed. It will be understood that the invention is not limited to the number of shutter positions indicated, but that the shutter may be placed at any position desired, its position usually being determined by preliminary tests and fixed for a given run of coal. It will be noted that bearing apertures 91 are provided in the walls of the air conduit at the rear end of the table, whereby the entire bed of materials may be subjected to air waves of the same pressure limits and in the same phase. The bearing apertures are provided with removable caps 92 for preventing escape of air when the shutter is mounted at another opening. The variably positionable wings 83 and 84 serve to accommodate the shutter to the sloping bottom of the air chamber at different points therealong.

Referring to Figs. 8 and 9, a further regulation and control of the lifting air currents may be provided when necessary or desirable. This further regulation comprises a refinement or localization of the zoning of the deck surface, for selectively controlling the relative intensity of the air current action with a very great degree of exactness and through a very wide range of variation in the amount of air supplied, in a plurality of sub-zones or sub-areas of each of the various zones or areas of a given air-perviousity.

In the embodied form of said means girder plates 111 are supported at their ends by the vibratable or reciprocable frame 19, 20, and extend preferably transversely forwardly and outwardly at the same angle with the separating partitions. These plates also conveniently support the deck supporting beams 110 by means of brackets 109. These girder plates constitute some of the side walls of a plurality of relatively small or localized air chambers beneath each of the various zones of differing air current intensity. Other chamber-defining plates or walls 117 cooperate with the plates 111, and these are preferably disposed longitudinally of the table, although this may be varied as desired. Plates 117 also serve conveniently to support the deck supporting beams 110. There are formed by the deck 10 and the plates 111 and 117 a plurality of chambers 118 beneath each zone area of the air-pervious deck. Referring to the means for selectively regulating the air current intensity in each of the chambers 118, each chamber is provided with a floor 119, each of these floors being provided with a plurality of apertures 120, and these apertures having a removable plug or stopper 121. The plurality of openable and closable apertures from the main air chamber into each of the sub-areal chambers beneath the various zone areas of the table provide an almost infinite capacity for regulating the

air intensity in each of these sub-areas in connection with the general zonal arrangement of the air currents. This feature of the invention, however, could be used independently of the general gradated zoning of the table if desired.

In the operation of the hereinbefore-described mechanism, the table may be regarded as having thereon a bed of the intermixed materials, such as run of the mine coal undergoing separation. The table is reciprocated through a short path, preferably with a slow rising forward motion and a quick descending rearward motion, the lifting air currents being forced upwardly through all parts of the bed with intensities dependent upon the degree of air-perviousity of the bed and the setting or regulation of the other air intensity controlling devices. The lifting air current at the rear end of the table separates and loosens the particles or pieces of material, and the coal or other lighter material is buoyed or lifted upwardly into a superior horizontally-disposed stratum and the rock and other impurities settle upon the table, and thereafter are forwarded by friction and inertia to a place of discharge. The stratifying and separating operation continues in like manner forwardly along the table as the bed progresses from the rear toward the front.

Due in a large measure to the differential air action on the different areas of the bed, whereby the rear portion of the bed is subjected to the largest amount of air of the maximum intensity, the largest pieces of rock or other heavier material settle immediately upon the table at or very near the place of feeding on of the material and are thereby separated from the mass of material, and are thenceforth progressed immediately to discharge by joint action of friction and inertia. The wave-like action of the air forces greatly enhances the rapidity and thoroughness of this stratification. The remaining portion of the mass flows freely forwardly along the table, the upper part consisting of already stratified and separated coal, and the lower part consisting of material yet intermixed, but rapidly undergoing the process of complete separation. As the material so moves forward, the smaller and smaller pieces of the heavier material progressively settle lower in the stratum, and, as they move into progressively decreasing areas of lifting air force, at one point or another finally sink behind the separating partitions and are immediately impelled to discharge at the side edge of the bed, while the overhead stratum of progressively purifying coal moves freely and directly forwardly to discharge over the front spillage edges 14. It will thus be seen that concurrently with the separating action there occurs an automatic classification of the refuse according to sizes, the greater portion of the large sizes of refuse being discharged through the rear discharge boxes, and the refuse in the forward boxes progressively decreasing in size as indicated.

In accordance with certain features of the invention, there is also effected a concurrent process of both cleaning and sizing the unsized coal, or equivalent lighter upper stratum of material. During the separating operation, and concurrently with the stratification, separation and cleaning of the impurities out of the coal, the coal is classified as to size positionally transversely of the table. That is, as the bed of materials progresses gradually forwardly along the table, undergoing stratification and separation, in the upper stratum of clean coal the larger pieces gradually work to the outer side edge of the table, and then travel forwardly to discharge at the forward end

of the table. The pieces of coal of next largest dimension gradually work to a position in the upper stratum of coal just within the aforesaid largest pieces, and travel forwardly in the bed to discharge at the forward end of the table, and so on across the table, the size of the coal in the upper, clean stratum decreasing transversely and gradually toward the lower side edge of the table and of the bed. Thus, the upper stratum of coal is discharged in pure or clean condition at the forward end of the table, and also in classified condition as to size.

The invention in its broader aspects is not limited to the specific mechanisms shown and described but departures may be made therefrom within the scope of the accompanying claims without departing from the principles of the invention and without sacrificing its chief advantages.

20 What we claim is:—

1. The process of separating intermixed divided materials varying relatively greatly in size, but varying relatively little in their specific gravities, which comprises maintaining a bed of the materials of substantial thickness in continuous progression over an air-pervious table, forcing lifting air currents upwardly through the bed to progressively stratify the materials in substantially horizontal superposed strata, whereby a lighter material forms a floatant superior stratum and a heavier material settles to the table surface, continuously and recurrently modifying the force of the air currents supplied to the bed in wave-like impulses between upper and lower limits, said upper and lower limits being different in different areas of the bed, and varying the relative extents of said different areas for materials having different characteristics.

2. The process of separating intermixed divided materials varying relatively greatly in size, but varying relatively little in their specific gravities, which comprises maintaining a bed of the materials of substantial thickness in continuous progression over an air-pervious table, forcing lifting air currents upwardly through the bed to progressively stratify the materials in substantially horizontal superposed strata, whereby a lighter material forms a floatant superior stratum and a heavier material settles to the table surface, continuously and recurrently modifying the force of the air currents supplied to the bed in wave-like impulses, subjecting one area of the bed to impulses between an upper and an intermediate limit and subjecting another area of the bed to impulses between an intermediate and a lower limit, and progressing the superior stratum of lighter material and the heavier material to different places of discharge.

3. The process of separating intermixed divided materials varying relatively greatly in size, but relatively little in their specific gravities, which comprises maintaining a bed of the materials of substantial thickness in continuous progression over an air-pervious table, forcing lifting air currents upwardly through the bed to progressively stratify the materials in substantially horizontal superposed strata, whereby a lighter material forms a floatant superior stratum and a heavier material settles to the table surface, continuously and recurrently modifying the force of the air currents supplied to the bed in wave-like impulses, subjecting a rear portion of the bed to impulses between an upper and an intermediate pressure limit, and subjecting a forward portion of the bed to impulses between an intermediate

and a lower limit, and progressing the superior stratum of lighter material and the heavier material to different places of discharge.

4. A mechanism for separating intermixed, divided materials varying relatively very greatly in size and varying relatively little in their specific gravities, which comprises an air-pervious table, feeding means adapted to maintain a bed of materials on the table undergoing separation, means for reciprocating the table, means for forcing lifting air currents upwardly through the bed of materials, whereby a lighter material stratifies as a floatant superior stratum and a heavier material settles to the table surface, means for continuously and recurrently modifying the force of the air currents supplied to the bed between upper and lower pressure limits, said limits being different at different areas of the bed, and means for varying the extent of said different areas, means for directing the settled heavier material transversely over the table by friction and inertia as soon as it settled, and means for discharging the superior lighter material.

5. A mechanism for separating intermixed, divided materials including in combination an air-pervious table, feeding means adapted to maintain a bed of materials on the table undergoing separation, means for supplying air under pressure to an air chamber beneath the table, and means located within the air chamber medianly of the ends of the table for modifying the pressure of the air supplied to produce a continuous series of recurrent wave-like impulses in the air supplied to the bed of materials whereby different areas of the bed are subjected to impulses of different force.

6. A mechanism for separating intermixed, divided materials including in combination an air-pervious table, feeding means adapted to maintain a bed of materials on the table undergoing separation, means for supplying air under pressure to an air chamber beneath the table, and means located medianly of the ends of the table for modifying the pressure of the air supplied to produce a continuous series of recurrent wave-like impulses in the air supplied to the bed of materials whereby different areas of the bed are subjected to impulses of different force and means for varying the position of said pressure-modifying means to change the pressures at different areas of the bed.

7. A process for separating intermixed divided materials varying relatively greatly in size but relatively little in their specific gravities, which comprises maintaining a bed of the materials of substantial thickness in progression over a vibrating air-pervious table, forcing lifting and loosening air currents through the moving bed to progressively form a superior stratum of floatant lighter material and to cause a heavier material to settle to the table by gravity, progressing the lighter material and the settled heavy material to different places of discharge, and supplying said air currents to the table in recurrent waves or pulsations which are out of phase and have different pressure limits in different parts of the table.

8. A mechanism for separating intermixed, divided materials varying relatively very greatly in size and varying relatively little in their specific gravities, which comprises an air-pervious table, feeding means adapted to maintain a bed of materials on the table undergoing separation, means for reciprocating the table, means

including an air-chamber beneath the table for forcing lifting air currents upwardly through the bed of materials, whereby a lighter material stratifies as a floatant superior stratum and a heavier material settles to the table surface, means for continuously and recurrently modifying the force of the air currents supplied to the bed between upper and lower pressure limits, comprising a rotatable shutter valve mounted across the air-chamber intermediate the ends of the table.

9. A mechanism for separating intermixed, divided materials varying relatively very greatly in size and varying relatively little in their specific gravities, which comprises an air-pervious table, feeding means adapted to maintain a bed

of materials on the table undergoing separation, means for reciprocating the table, means including an air-chamber beneath the table for forcing lifting air currents upwardly through the bed of materials, whereby a lighter material stratifies as a floatant superior stratum and a heavier material settles to the table surface, means for continuously and recurrently modifying the force of the air currents supplied to the bed between upper and lower pressure limits, comprising a rotatable shutter valve mounted across the air chamber intermediate the ends of the table and means for varying the position of the valve along the air chamber.
